H. C. PITTMAN:

Inventor:

By

Robert W. Kandall

Attorney.

UNITED STATES PATENT OFFICE

HARRY C. PITTMAN, OF RICHMOND, INDIANA

MOTOR PROTECTOR AND SPEED ACCELERATOR

Application filed January 12, 1931. Serial No. 508,150.

The objects of this invention, broadly speaking, are the provision of a motor protector which is simple in construction, requiring no attention for its proper functioning, 5 easily applied in proper position, which will give a maximum of efficiency in practice, and which can be manufactured, sold, and installed with a minimum of expense devoted thereto.

10 More specifically stated, my object is the provision of means for the protection of motors, or other mechanisms, from adverse weather and atmospheric condition, and from other conditions which may develop.

15 Another object is the provision of a protector for air craft motors, to decrease the air resistance and thereby permit the air craft to travel more rapidly and with less fuel consumption, in addition to protecting the 20 motor thereof from cold or adverse atmospheric conditions.

Other objects and particular advantages of my invention will be brought out and observed by the usual motor and air craft mechanician in the course of the following description, and that which is new will be pointed out in the appended claim.

The best means, to me known at this time, for carrying out the principles of my invention, in a mechanically efficient and an economical manner, is shown in the accompanying drawing, in which—

Figure 1 is a side elevation of the front portion of an air-plane, showing my invention in connection therewith. Figure 2 is a front end elevation of the same. Figure 3 is a perspective view of the fixed or stationary member of my protector. And Figure 4 is a perspective view of the revolvable or movable member alone.

Similar indices designate like parts throughout the several views, in which the parts which are old, and to which I make no claim, are indicated by letters of reference, 45 and those which are new and form a part of my invention are designated by figures of reference.

In order that the construction, the application thereof to its proximate uses, and the 50 several advantages thereof may be more fully

and clearly understood and appreciated, I will now take up a detail description thereof, in which I will set forth the same as fully and as comprehensively as I may.

Now, taking up a description of my invention as applicable to an aero-plane, or other motorized air vehicle: In this instance letter G denotes the forward or nose portion of an air-plane. Mounted in front of the said nose, and carried thereby, is the circular motor H. 55 Letter I denotes the propeller shaft, which is rotated by said motor, and which turns the blades J, which are secured to a hub, the latter being connected on the shaft I, but is not shown herein.

60 The relatively stationary, or fixed, portion of my protector forms a jacket comprising the member 17, which partly incloses the motor H, with its rear portion secured to the front portion of the nose G. Forward of the motor H, the member 17 merges into the forwardly 65 tapering member 18, which latter is located concentrically with the shaft I, and it in turn merges into the disc 19, with the shaft aperture 20 formed through the center thereof.

70 Located immediately forward of the said rear portion of the protector, is the front portion thereof, which is in the nature of a cone forming a jacket, comprising the conical portion proper, denoted by numeral 21. The forward end of said cone portion terminates in the rounded end 22, and the rear end of said cone is closed by the disc 23, which latter has 75 an aperture 24 formed through the center thereof, for the shaft I.

80 Formed through the central portion of the member 21 are the oppositely disposed apertures 25, through which the blades J extend.

85 When the said parts are assembled, as in Fig. 1, for instance, the discs 19 and 23 are located near each other, but no part of the stationary member, shown in Fig. 3, will contact with the rotary member shown in Fig. 4.

90 It will now be apparent that, with my invention attached thereto, the air-plane may 95 function in the usual manner and without any interference by reason of my attachment.

As the air-plane moves forward it is apparent that my attachment will protect the motor from direct contact with cold air, but 100

still permitting the motor to receive the correct amount of air for its proper functioning.

Also it will be observed that the shape of my protector will enable the air-plane to cut through the air, even with adverse air currents, and high winds, with a minimum of air resistance thereto, thereby allowing the vehicle to travel more rapidly, with less fuel consumption, and with greater safety.

10 It is to be understood that various changes may be made in the several details herein set forth without departing from the spirit of the invention or sacrificing any of the advantages thereof which are new and useful.

15 What I claim is:

In combination with a motor having a shaft extending forwardly therefrom and adapted to be rotated thereby and propeller blades carried by the projecting portion of said 20 shaft; a relatively stationary jacket member extending partly around the motor with its forward end forming a disc at right-angles to and concentric with said shaft, a conical jacket member concentric with said shaft and 25 secured thereto with its rear end located near to and corresponding with said disc and with said blades projecting outwardly through said conical jacket member.

HARRY C. PITTMAN.
